UNITED STATES PATENT OFFICE.

ALBERTUS O. SLENTZ, OF CANTON, OHIO, ASSIGNOR TO THE CANTON FOUNDRY AND MACHINE COMPANY, OF CANTON, OHIO, A CORPORATION OF OHIO.

COMBINED SHEARS AND SHEET-METAL BRAKE.

1,036,359.

Specification of Letters Patent. Patented Aug. 20, 1912.

Application filed February 28, 1910. Serial No. 546,330.

To all whom it may concern:

Be it known that I, ALBERTUS O. SLENTZ, a citizen of the United States, residing at Canton, in the county of Stark and State 5 of Ohio, have invented certain new and useful Improvements in Combined Shears and Sheet-Metal Brakes; and I do hereby declare that the following is a full, clear, and exact description of the same, reference being had to the accompanying drawing, making a part of this specification, and to the numerals and figures of reference marked thereon, in which—

Figure 1 is a front side elevation. Fig. 2 is an end view showing transverse section of the power shaft. Fig. 3 is a vertical section on line 3—3, Fig. 1. Fig. 4 is a view showing a portion of the bed plate illustrating a sheet of metal thereon, also showing the 10 knife and brake die or blade and heads in elevated position or normal position. Fig. 5 is a side elevation of one of the combined pitman, cam and gear wheels showing the same in relative position with the parts shown in Fig. 4, also illustrating the brake die actuating mechanism and a portion of the pitman. Fig. 6 is a view similar to Fig. 4, showing the knife brought to its lowest position and the brake die partially lowered. Fig. 7 is a 15 side elevation of one of the combined pitman, cam and gear wheels showing the parts in position relative to the position of the parts shown in Fig. 6, also showing the brake die actuating mechanism also a portion of the pitman. Fig. 8 is a view showing a portion of the bed plate illustrating the brake die brought to its lowest position and the knife partially elevated, also showing in transverse section a finished product 20 or folded piece of metal. Fig. 9 is a view showing in perspective one of the combined pitman, cam and gear wheels showing the pinions designed to impart motion to said wheel and the clutch mechanism, also showing the track or way designed to hold the 25 clutch members in engagement. Fig. 10 is a view showing portions of the knife carrying and brake die heads, also showing a portion of one end of the frame and illustrating 30 the connecting and guide pins. Fig. 11 is a side elevation of one of the combined pit-

man, cam and gear wheels showing the parts in position relative to the position of the parts shown in Fig. 8, also showing the 55 brake die actuating mechanism and a portion of the pitman.

The present invention has relation to a combined shear and sheet metal brake and more specifically designed to cut strips of metal from large sheets and to fold said cut 60 strips into U-shaped position, the finished product to be used for window screen frames and other analogous purposes.

Similar numerals of reference indicate corresponding parts in all the figures of the 65 drawings.

In the accompanying drawings, 1 and 2 represent the end frames or standards which are substantially of the form shown in the drawings, and are held in proper spaced relationship with reference to each other by means of the lower tie bars 3 and 4 and the bed plate 5. In the end frames or standards 1 and 2 is properly journaled the power shaft 6, one end of which is provided with 70 the power wheel 7 which is driven from any source of power. Upon the power shaft 6 are mounted pinions 8, one of said pinions being shown in Fig. 2. The pinions 8 mesh with the pinions 9 and 10, said pinions being 75 mounted upon the shaft 11, which shaft is properly journaled in the end frames or standards 1 and 2. The pinions 9 and 10 mesh with the combined pitman cam and gear wheels 12 and 13, said wheels being 80 mounted upon the stud bearings 14, which stud bearings are connected to the end frames or standards 1 and 2 in the usual manner.

The top or upper portions of the end 85 frames or standards 1 and 2 are each provided with the slots or ways 16, through which slots or ways are passed the connecting and guide pins 17 and 18. Connecting and guide pins 17 are pivotally attached to 90 the pitman 19, the bottom or lower ends of said pitman being pivotally attached to the wheels 12 and 13. The connecting pins 17 are secured to the ends of the knife carrying 95 head 20 and pins 18 are secured to the brake 100 die carrying head 21 in any convenient and well known manner or if desired said con-

necting pins may be formed integral with the heads 20 and 21. The head 20 is provided with the downward extending flange 22 to which flange is attached the knife or shear blade 23 by means of the clamping bolts 24. To the brake die head 21 is attached in any convenient and well known manner the brake die 25. It will be understood that when rotary motion is imparted 5 to the wheels 12 and 13 a reciprocating movement will be imparted to the knife head 20 by means of the pitmen 19. The wheels 12 and 13 are each provided with the cams 26, which cams are for the purpose 10 of imparting a reciprocating movement to the slotted bars 27 by means of the rollers 28, which rollers are properly journaled in the bottom or lower ends of the slotted bars 27. For the purpose of guiding the slotted 15 bars and at the same time causing said bars to move up and down in a true vertical plane, the studs 14 are provided with the squared portions 29, the vertical faces of which are located against and in contact 20 with the inner walls of the slotted bars 27. It will be understood that the blocks 29 should be so fitted and adjusted with reference to the slots in which they are located 25 that free reciprocating movement can be imparted to the slotted bars.

From the top or upper ends of the slotted bars 27 extend the arms 30, which arms are connected to the pins 18. It will be understood that when rotary motion is imparted 30 to the wheels 12 and 13 a reciprocating movement will be imparted to the brake die carrying head 21, but by reason of said brake head being actuated by the cam grooves 26, the slotted bars 27 and the rollers 28 a different timed movement will be imparted to the brake die carrying head from that imparted to the knife carrying head, owing to the fact that the latter is actuated by the pitmen 19. This different 40 timed movement is for the purpose herein-after described. Below the brake die carrying head is located the bed plate or die 5, which bed plate is secured to the end members 1 and 2 by means of the flanges 31 and the bolts 32 or their equivalents. The bed plate or die 5 is provided with the shear flange 33 and the slot 34. Upon the bed plate 5 is located the gage plate or bar 35. For the purpose of imparting movement to 45 the machine proper during the time the power shaft 6 is rotated the clutch members 36 and 37 are provided. The clutch member 37 being rotatably and slidably mounted upon the shaft 6 and when said clutch members are brought into engagement with each other movement will be imparted to the 50 movable parts of the machine proper, but when said clutch members are out of engagement the machine will remain at rest.

For the purpose of holding the clutch

member 37 out of engagement with the clutch member 36 the lever 38 is provided, which lever is pivoted to the bracket 39 or its equivalent, said lever being connected to the slidable clutch member 37 in the usual manner and for the purpose of normally holding the lever in the position to throw the clutch proper out of action or the clutch members out of engagement with each other the spring 40 is provided, which spring is located around the rod 41, which rod is connected to the bell crank 42 and also to the bottom or lower end of the lever 38. The ends of the spring abut against the standard 2 and the bottom or lower end of the lever 38, the tension of which spring forces the bottom or lower end of the lever 38 away from the standard 2 and at the same time holding the clutch member 37 out of engagement with the clutch member 26. 55 When it is desired to bring the machine into action the treadle 43 is moved downward, said treadle being pivotally mounted upon the tie bar 3 or its equivalent, which downward movement rocks the bell crank 42 by means of the connecting link 44, which link is connected to said bell crank and treadle. By this downward movement of the treadle 43 the bottom or lower end of the lever 38 is moved toward the standard 2, 60 thereby, coupling up the clutch members 36 and 37.

It is of importance that no stop of the machine proper be permitted after it has been put in motion until the wheels 12 and 13 have made a complete revolution, thereby bringing the movable parts into the same position that they were before the machine was put in action. In order to provide for stopping the machine at a time when the heads carrying the knife and brake die are in their highest position or in the position illustrated in Fig. 4, but permitting the wheels 12 and 13 to make a complete revolution, the flange or track 45 is provided, 65 which flange or track is provided with the spaced ends 46. It will be understood that when the lever 38 is moved outward at its upper end or away from the flange or track 45 the clutch members are brought into engagement and the machine proper set in motion and when in motion the upper end of the lever 38 is held in position to couple the clutch by means of the angled portion 70 47, but when the lever 38 is permitted to move toward the wheel 12 the clutch members will be disengaged and the machine thrown out of action. The automatic stopping of the machine is brought about by reason of the action of the spring 40.

For the purpose of providing a shear cut the knife or shear blade 23 is so adjusted, or its cutting edge so located with reference to the shear flange 33, that it will be located at an angle to said shear flange, this feature 75

being best illustrated in Fig. 1. It will be understood that the knife 23 should be so adjusted upon its head that it will only move downward a sufficient distance to cut the sheet from which the U-shaped or folded strip such as 48 is formed as hereinafter described. After the knife 23 has cut the strip designed to be folded it is necessary to move the brake die 25 downward and independent of the downward movement of the knife. This downward movement of the brake die is brought about by means of the cams 26 and the intermediate mechanism between said cams and the head carrying the brake die 25. The cams are so formed that the proper timed movement will be imparted to the knife and brake die to first cut the metal and second to form the metal thus cut. As the brake die 25 moves downward it comes against the upper surface of the sheet of metal cut by the knife, thereby forcing the metal through the slot 34, and breaking or folding the sheet into substantially the form shown in Fig. 8.

It will be understood that there should be no relative movement between the knife or shear blade 23 and the head 20 and its flange 22 after said knife has been brought to its proper adjustment with reference to the head and in order that the strain may be taken from the clamping bolts 24, the lug bolts or set screws 49 are provided, which are arranged so that their bottom ends will bear against the top edge of the knife. This feature is best illustrated in dotted lines. In order that the knife can be properly adjusted the flange 22 is provided with the slots 50, through which slots the bolts 24 pass.

For the purpose of automatically elevating the treadle 43 after it has been depressed the rods 51 and 52 are provided, the rod 51 being connected to the treadle and the rod 52 to the bed plate 5 or its equivalent and said rods lapped and the spring 53 provided. The parts for automatically operating the treadle are common and well known and hence no detailed description is necessary, said parts being shown conventionally.

For the purpose of delivering the finished product at one side of the machine proper the inclined plates or bars 54 are provided, which plates are inclined downward as illustrated in Fig. 3.

The shear flange 33 is so formed that its shear edge will be located a short distance above the top of the bed plate 5 and the gage plate or bar 35 is formed of such a thickness and so spaced from the flange 33 that it will properly gage the sheet of metal designed to be cut when the sheet is located upon the portion of the bed plate designed to support the sheet. It will be understood that after the strip designed to be folded has been cut from the main sheet it is free to drop onto that portion of the bed plate between the gage plate and the shear flange so that when the brake die 25 is brought down and onto the strip cut, there can be no slipping or sliding movement of the strip from which the folded strip 48 is produced or formed.

It will be understood that by the peculiar arrangement of the device by means of which reciprocating movement is imparted to the knife head and knife and to the die head and brake die, that during a portion of the downward movement of the said parts they move in unison and that for another portion of their downward movement they do not move in unison, that is to say the brake die is moved downward to a point lower than the extreme downward movement of the shear and that during this further downward movement of the brake die the shear is raised up and brought to its normal position, after which the brake die and its head is brought upward to its normal position.

Having fully described my invention what I claim as new and desire to secure by Letters Patent, is—

1. In a machine of the class described, the combination of standards, a bed plate, a knife carrying head, a die carrying head, a knife secured to the knife carrying head and a die secured to the die carrying head, and combined gear, cam and pitman wheels adapted to reciprocate said knife carrying head and die carrying head.
2. In a machine of the class described, the combination of a bed-plate, standards adapted to support said bed-plate, a reciprocating knife carrying head, a knife secured thereto, a reciprocating die carrying head and a die secured thereto, combined gear, cam and pitmen wheels and intermediate means adapted to reciprocate said knife carrying head and said die carrying head, one revolution of said wheels completing one operation of said reciprocating heads.
3. In a machine of the class described, the combination of a bed plate, standards adapted to support said bed plate, a reciprocating knife carrying head, a knife secured to said head, a reciprocating die carrying head and a die secured to said head, combined gear, cam and pitmen wheels adapted to reciprocate said heads, one revolution of said wheels completing one operation of said heads, and means for stopping said wheels at the end of each revolution.
4. In a machine of the character described, the combination of a bed-plate and standards, a reciprocating knife carrying head, a knife secured to said head, a reciprocating die carrying head and a die secured to said die head, combined gear, cam and pitmen wheels, means intermediate said gear, cam and pitmen wheels adapted to re-

reciprocate said die and knife carrying heads, one of said wheels being provided with a concentric track, a spring pressed clutch controlling member adapted to allow said 5 wheel to make one revolution and means for operating said lever.

5. In a machine of the class described, a bed plate, a knife carrying head, a die carrying head, a knife and die secured to said 10 heads, respectively, combined gear, cam and pitmen wheels, means intermediate said gear, cam and pitmen wheels adapted to reciprocate, said knife and die carrying heads, one of said wheels being provided with a 15 concentric track, a spring pressed clutch controlling lever adapted to allow said wheels to make one revolution and means for operating said lever.

6. In a machine of the character described, the combination of a bed plate and standards, a knife carrying head, a knife secured to said head, a brake die carrying head and a brake die secured to said die carrying head, the bed plate provided with 20 a slot adapted to receive the brake die, combined gear, cam and pitmen wheels adapted to reciprocate said knife carrying head and brake die carrying head in unison for a portion of their travel, then to move said 25 knife carrying head forward, then to return said knife carrying head and move said brake die carrying head forward and then to return said die carrying head.

7. In a machine of the character described, the combination of a bed plate and standards, a knife carrying head, a knife secured to said head, a brake die carrying head and a brake die secured to said die carrying head, the bed plate provided with 30 a slot adapted to receive the brake die, combined gear, cam and pitmen wheels adapted to reciprocate said knife carrying head and brake die carrying head in unison for a portion of their travel, then to move said 35 knife carrying head forward, then to return said knife carrying head and move said brake die carrying head forward and then to return said die carrying head, one revolution of said wheels completing one operation of said heads and means for stopping said wheels at the completion of each revolution.

8. In a machine of the character described, the combination of a bed plate and standards, a knife carrying head, a knife secured to said head, a brake die carrying head and a brake die secured to said die carrying head, the bed plate provided with a slot adapted to receive the brake die, combined gear, cam and pitmen wheels adapted 40 to reciprocate said knife and brake die in unison for a portion of their travel, then to move said knife forward, then to return said knife and move said brake die forward through the slot in said bed plate and then 45 to return said brake die.

9. In a machine of the character described, the combination of a bed plate and standards, a knife carrying head, a knife secured to said head, a brake die carrying head and a brake die secured to said die carrying head, the bed plate provided with a slot adapted to receive the brake die, combined gear, cam and pitmen wheels, pitmen connecting said wheels to said knife carrying head, and adapted to reciprocate 70 the same, cam tracks upon said wheels and intermediate means for reciprocating said die carrying head.

10. In a machine of the character described, a bed plate, a knife carrying head, a knife secured to said head, a die carrying head, a die secured to said die carrying head, slotted bars connected to said die carrying head, pitmen connected to said knife carrying head, combined cam, gear and pitmen wheels adapted to reciprocate 80 said knife carrying head and brake die carrying head in unison for a portion of their travel, then to move said knife carrying head forward, then to return said knife carrying head and move said brake die carrying head forward and then to return 85 said brake die carrying head, one revolution of said wheels completing one operation of said heads, cam tracks located upon the inner faces of said wheels, rollers located upon the lower extremities of said slotted bars, said rollers operated within said cam tracks, said pitmen pivotally connected to said wheels, one of said wheels provided 90 with a concentric track upon its outer face, and means for stopping said wheels at the completion of each revolution.

11. In a machine of the character described, the combination of a bed plate and standards, a knife carrying head, a knife secured to said head, a brake die carrying head, a brake die secured to said brake die carrying head, the bed plate provided with a slot adapted to receive the brake die, combined gear, cam and pitmen wheels adapted to reciprocate said knife carrying head and brake die carrying head in unison for a portion of their travel, then to move said 105 knife carrying head forward, then to return 110 said knife carrying head and move said brake die carrying head forward and then to return said brake die carrying head, one revolution of said wheels completing one operation of said heads, cam tracks provided 115 upon the inner face of each of said wheels, bars connected to said brake die carrying head, rollers located at the lower extremities of said 120 bars, said rollers adapted to travel within said cam tracks, pitmen connected to said knife carrying head, said pitmen pivotally connected to said wheels, a concentric track located upon the outer face 125 of one of said wheels, a lever pivoted intermediate its ends upon one of said standards, 130

one end of said lever adapted to ride upon
said concentric track, a power shaft jour-
naled in said standards, a clutch located
upon said power shaft, the opposite end of
5 said lever connected to said clutch, means
for normally holding said clutch open and
means for closing said clutch.

In testimony that I claim the above, I
have hereunto subscribed my name in the
presence of two witnesses.
